UNITED STATES PATENT OFFICE

2,432,252

HAND ELECTRIC CLOTHES PRESSER

William H. Ryan, River Forest, Ill.

Application October 28, 1944, Serial No. 560,835

1 Claim: (Cl. 38—72)

1

My invention relates to hand type electric clothes presses, and one object is to provide a presser of this kind which exerts a strong grip on the material pressed, whereby to procure a highly efficient pressing operation.

A further object is to design the novel presser as a development of a hand tool of the spring plier or curling iron variety, wherein gripping pressure on the handles opens a pair of jaws against spring resistance, the jaws carrying presser units designed to engage the material to be pressed when the pressure on the handles is relaxed.

Another object is to include a removable intermediate plate in the novel presser which serves as an ironing board or base to facilitate the simultaneous pressing of a pair of trouser legs, effecting a saving of time.

An important object is to construct the novel presser along lines of simplicity and durability.

With the above objects in view and any others which may suggest themselves from the description to follow, a better understanding of the invention may be had by reference to the accompanying drawing, in which—

Fig. 1 is a side elevation of the presser opened to receive the work;

Fig. 2 is a top plan view;

Fig. 3 is a section on the line 3—3 of Fig. 1 showing one type of support for the intermediate plate referred to above;

Fig. 4 is a view similar to Fig. 3 and showing a modified support; and

Fig. 5 is a view showing the manner in which the presser is used.

In accordance with the foregoing, specific reference to the drawing indicates the frame of the presser at 10, and it will be apparent that the same has the general formation of a pair of pliers, one end of the frame being developed with the usual handles 11 and the other with flat jaws 12 and 13. The usual medial pivot 14 is employed to hold the frame together, and a torsion spring 15 is lodged in the hollow of the frame in the usual manner for the purpose of urging the jaws 12 and 13 toward each other.

For the purpose of the present invention, the jaws are provided on their inner sides with presser units 16 and 17. These are flat, hollow bodies of sheet metal which contain electrical heating elements 18 lodged between mica insulators 19, so that the units 16 and 17 become constituted as pressing irons in relation to any cloth or garment or other material which may be placed therebetween. The units 16 and 17 carry con-

2

necting posts 20 from which electrical conductors 21 extend to be joined in the form of a current supply cord 22, the same preferably entering the presser by way of an opening 23 in one of the handles 11.

While the presser unit 17 is solidly connected with the jaw 13, the presser unit 16 is floatingly disposed. As shown, a pair of posts 24 rise from the center region of the unit 16 to pass freely through openings 25 in the jaw 12 and terminate with heads 26. Thus, when the presser is closed, the unit 16 readily adjusts itself to bear flatly on the unit 17 and will be free to bear evenly on the work between the presser units irrespective of the angle of the jaws.

It will now be apparent that with the presser opened to the extent shown in Fig. 1, it is possible to insert the material of a garment or other cloth article between the presser units 16 and 17, so that when the handles are released and the electrical current turned on—by a suitable switch or button not shown—the pressing operation will begin.

The intermediate plate previously referred to is shown inserted in the presser and denoted by the numeral 27. This plate is flat and of sheet metal; and it is of approximately the same size as the units 16 and 17. The plate is designed to be supported midway between these units, and one form of the support is a pair of rods 28 forming part of an arch 29 secured by rivets 30 or other means to the plate 27. The rods extend rearwardly from the plate to enter tubular sockets 31 carried by the jaw 13 of the presser. The fit of the rods in the sockets is snug, so that the plate 27 becomes firmly supported in the position shown. Now two pieces of material can be inserted in the presser on opposite sides of the plate and the latter employed in the manner of an ironing board or base against which the units 16 and 17 press the material. This feature is especially of advantage in the case of trousers, enabling both legs thereof to be pressed in one operation. It is understood, of course, that only a portion of any garment is pressed at one time, as illustrated in Fig. 5. While this figure shows a presser of average size, it is possible to make the same or its presser units 16 and 17 larger in order to cover the area between the crease and the medial seam in a pair of trousers.

Fig. 4 shows a modification of the plate support wherein the arch 29 is extended with spring arms 32. These are projected with inward jaws 33 which are adapted to enter openings 34 in the

lower frame member 10 to make a snug fit therein. The arch 29 is thus firmly connected to the jaw 13 and forms a solid support for the plate 27.

It will be evident from the above description that I have provided a hand presser which is not only light and easily maneuverable, but is of a form to be firmly held in the hand and easily operated to open and receive the work. Ordinarily, it may be used without the intermediate plate 27 by simply removing the same. Yet, this plate is easily attachable to permit double work to be done simultaneously. In such case it is feasible to pre-heat the plate 27 by first allowing the units 16 and 17 to close upon the same while the heat is on, so that the plate will be hot when the double work is inserted. Further, the floating presser unit 16 is a feature which automatically adjusts the presser to exert uniform pressure on the work. Further, it is noted that hand pressure is only momentarily needed for the purpose of opening the presser jaws, and that no manual effort is required to do the actual pressing because the force of the spring 15 will do this either momentarily or as long as required. While the presser is capable of exerting considerable force on the work being pressed, it can be made very light throughout, so as not to impose any fatigue while it is held or moved from place to place along the work. Altogether, the novel presser forms a neat, compact, efficient and durable implement which is designed to serve as a handy substitute for the much heavier pressing iron and the ironing board usually required for the same.

While I have described the invention along spe-

cific lines, various minor changes or refinements may be made therein without departing from its principle, and I desire to consider such changes and refinements as coming within the scope and spirit of the appended claim.

I claim:

A hand-type clothes presser comprising an implement of plier form and containing a spring to gather the jaws, flat and hollow members carried by the jaws in opposed relation, heating units inside said members, a plate between and in substantial parallelism to said members, receptacles carried by one of said jaws, and rods extended from the plate and removably held in said receptacles for the support of the plate from said jaw.
